(57) **CLAIM**

The ornamental design for a saw blade, as shown and described.

DESCRIPTION

FIG. 1 is a front elevational view of a saw blade showing my new design;

FIG. 2 is a rear elevational view thereof;

FIG. 3 is a top plan view thereof

FIG. 4 is a bottom plan view thereof

FIG. 5 is right side elevational view thereof;

FIG. 6 is a left side elevational view thereof;

FIG. 7 is a perspective view taken from the front, right side and top of the saw blade;

FIG. 8 is an enlarged, sectional view thereof, taken along lines 8—8 in FIG. 1;

FIG. 9 is an enlarged, sectional view thereof, taken along lines 9—9 in FIG. 1; and,

FIG. 10 is an enlarged, sectional view thereof, taken along lines 10—10 in FIG. 1.

The portion of the article depicted in broken lines is for illustrative purposes only and forms no part of the claimed design.
